UNITED STATES PATENT OFFICE.

CHARLES F. KETTERING, OF DAYTON, OHIO, ASSIGNOR TO THE DAYTON ENGINEERING LABORATORIES CO., A CORPORATION OF OHIO.

BINDING-POST.

1,089,771.

Specification of Letters Patent. Patented Mar. 10, 1914.

Application filed November 14, 1910. Serial No. 592,293.

To all whom it may concern:

Be it known that I, CHARLES F. KETTERING, a citizen of the United States, residing at Dayton, county of Montgomery, and 5 State of Ohio, have invented certain new and useful Improvements in Binding-Posts, of which the following is a full, clear, and exact description.

This invention relates to improvements in 10 binding posts for clasping the terminals of electric wires to secure the same firmly in position but available for ready detachment of the terminal from the binding post; and among the objects of this improvement are 15 to provide not only a small and inexpensive device of this sort, but one which shall also hold the terminal very securely against accidental separation from the binding post, and shall also permit the terminal to be very 20 quickly attached or detached.

With these and incidental objects in view, the invention resides in certain novel combinations of parts, a preferred form of embodiment which is shown in the accompanying 25 drawings.

In said drawings, Figure 1 represents a partly sectionalized view of this improved binding post, showing the terminal clasped in place. Fig. 2 represents a side elevation 30 of the binding post with the clamping members separate and the terminal just in process of being inserted between the clamping members. Fig. 3 represents a sectional view along the line 3—3 of Fig. 1 showing the 35 terminal fully pushed into place. Fig. 4 represents a similar sectional view showing the terminal only partly in place.

The binding post as shown in the aforesaid views, comprises upper and lower clamping members 20 and 21 respectively. The lower clamping member is provided with a bolt 22 and nut 23 adaptable to fasten the binding post to any desired object.

Extending upward from the lower clamping member 21, is what may be termed a locking shoulder 24, which is circular in shape as shown in Figs. 3 and 4. Extending farther upward is a central shaft 25 which for convenience may be termed a 50 guiding shaft as will appear later. At the top of this shaft 25 is a head 26. The shaft 25 extends up through an aperture in the base of the upper clamping member 20 and between the said head 26 and the base plate 55 of the member 20, there is a coil-spring 28

which spring presses the upper clamping member downward toward the lower clamping member 21. The upper clamping member 20 is formed with a knob 29 so that this upper member may be pulled upward against spring tension to separate it from the lower member in the manner shown in Fig. 2 so that the terminal 30 may be inserted. This terminal 30 is shown in the present case in the shape of a flat plate and is intended to be the terminal of the electric wire which it is desired to attach and detach from this binding post. The periphery of this terminal is formed with a slotted portion 31 leading to an enlarged central opening 32. This central opening 32 is slightly larger than the diameter or contour of the aforesaid locking shoulder 24. The width of the slot 31 however is slightly smaller than the said locking shoulder 24. Moreover the slot 31 is slightly larger than the shaft 25, so that as shown in Fig. 4, the terminal may be pushed inward between the two clamping members, as shown in Fig. 2, by having the terminal raised sufficiently to clear the locking shoulder 24 until the terminal is pushed all the way inward. As soon as this point is reached, the terminal may be dropped into the position shown in Fig. 1, in which case it will rest securely clamped between the two spring-pressed clamping members. The terminal cannot then be pulled out sidewise because the locking shoulder 24 is larger than the peripheral slot 31. The only way of removing the terminal is to pull upward on the upper clamping member 20 so as to separate the clamping members as shown in Fig. 2, in which case the terminal may be raised to clear the locking shoulder and then the slotted portion 31 is wide enough to permit withdrawal of the terminal past the shaft 25. Thus the real locking feature of the device is the lock-shoulder 24 acting in coöperation with the enlarged aperture 32 of the terminal, and preventing the terminal from being removed unless the clamping members are separated. But the shaft 25 acts as a convenient guide for the slotted portion 31 to permit the quick adjustment of the terminal into place and likewise although the terminal is open on this one side, the smaller width of the slot as compared with the locking shoulder, prevents lateral withdrawal of the terminal.

Although I have shown this one form of 110

the invention as a preferred form, it is to be understood that various changes may be made therein without departing from the spirit and scope of the present invention as set forth in the appended claims.

5 What is claimed is as follows:

1. A binding post comprising two confronting clamping members, one of the same having a lock projection extending toward 10 the other member, resilient means for normally maintaining said members in clamping position, and a terminal for clamping between said two members, said terminal being provided with an aperture slightly 15 larger than the contour of said locking shoulder, whereby to permit clamping of the terminal between said clamping members but preventing lateral withdrawal of the terminal without separation of the clamping 20 members.

2. A binding post comprising the combination with two spring pressed clamping members, one of said members being provided with a lock projection extending toward 25 the other member, and a guiding shaft extending from said locking shoulder; of a terminal having a peripheral slot of less width than the contour of said locking shoulder but of greater width than said 30 guiding shaft, and also formed with a central aperture connected with said peripheral slot and constructed of slightly larger contour than said locking shoulder, substantially as and for the purpose described.

3. A metallic terminal for an electrical element, having a spindle of various diameters; a metallic plate connected to a high tension wire and having a side opening to engage the spindle, the diameter of said 35 opening being larger than the width of its mouth and the smallest diameter of the spindle, while the width of its mouth is 40 smaller than the largest diameter of the

spindle; and means whereby the plate may be held in operative engagement with the 45 spindle.

4. A metallic terminal for an electrical element, having a spindle provided with a step of larger diameter than that of the spindle; a metallic plate connected to a high 50 tension wire and having a side opening the diameter of which is larger than that of the step, while the width of the mouth of the opening is larger than the diameter of the spindle, but smaller than the diameter of 55 the step; and means whereby the larger portion of said opening may be held in engagement with the step when the plate embraces and engages the step.

5. A binding post, comprising a hollow 60 clamping member; a coöperating clamping member having a reduced shank extending into said first named clamping member; an enlarged head secured to said shank member; a locking projection secured to said coöperating clamping member and extending toward the opposite member; spring means located about the shank of said coöperating member and operable to maintain the said members in clamping position; and a terminal provided with an aperture slightly 65 larger than the contour of said locking member, said terminal being provided with an opening slot communicating with said aperture of less width than the diameter of 70 said locking projection and of greater width than the diameter of the shank portion of 75 said coöperating clamping member.

In testimony whereof I affix my signature in the presence of two subscribing witnesses.

CHARLES F. KETTERING.
